NURSING BOTTLE HOLDER

John Jacob Lawrence, Chester, Pa.

Application December 2, 1943, Serial No. 512,614

4 Claims. (Cl. 248—103)

The present invention relates to new and useful improvements in nursing bottle holders for baby carriages and has for its primary object to provide a device of this character adapted for attaching to a baby carriage for holding the bottle in a convenient position for use by the baby.

A further object is to provide novel means for adjusting the bottle in a desired position.

Another object is to provide a device of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary side elevational view of a baby carriage showing the bottle holder in position thereon.

Figure 2 is a top plan view.

Figure 3 is a longitudinal sectional view taken on a line 3—3 of Figure 2.

Figure 4 is a transverse sectional view taken on a line 4—4 of Figure 2.

Figure 5 is a sectional view through the adjustable arm of the holder taken on a line 5—5 of Figure 2.

Figure 6 is a perspective view of one of the carriage clamps.

Figure 7 is a perspective view of the lower end of the adjustable arm, and

Figure 8 is a perspective view of one of the retaining pins for the arm.

Referring now to the drawings in detail, the numeral 5 designates the body of a conventional baby carriage which includes the side walls 6—6 and to which the top 7 is pivotally attached by bolts and wing nuts 7'—7'.

A pair of brackets 8—8 are constructed with spaced legs 9—9 positioned against the outer sides of the walls 6—6 and secured thereto by the bolts and wing nuts 7'—7', the upper portion of the brackets including vertically spaced flanges 10—10 between which short bars 11—11 are positioned for resting on the upper edges of the walls 6—6.

Also positioned between the flanges of one of the brackets is a bar 12 secured thereto by a bolt 13, the outer end of the bar being hollow for slidably receiving one end of a bar 14 having its other end secured between the flanges

of the other bracket by a screw 15. To compensate for the variation in thickness of the bars 12 and 14 and to secure the bars in a horizontal position transversely of the carriage, a spacing block 16 is inserted between the flanges 10 and the upper edge of the body of the carriage at the side thereof to which the narrow bar 14 is attached.

The bars 12 and 14 are square shaped in cross-section and mounted on the bar 12 is a pair of disks 17—17 having central openings 18—18 for conformably receiving the bar to prevent rotation of the disks. The disks are also provided with spaced aligned openings 19 adjacent their edges

15 for receiving pins 20 and 21 therein.

An arm 22 has one edge resting on the bar 12 between the disks and its opposite edge is formed with teeth 23 between which one or more pins 20 are received transversely of the arm to secure the arm in vertically adjusted position. By changing the position of the pins in the openings 19 the arm 22 may be adjusted about the axis of the disks to also raise or lower the outer end of the arm.

25 A nursing bottle 24 is secured to the outer end of the arm by a pair of clamps 25—25 with the nipple 26 on the bottle projecting downwardly beyond the arm in a convenient position for use by a baby lying in the carriage.

30 The lower end of the arm 22 is covered by a strip of rubber or other soft material 27 to prevent injury to the baby. In the operation of the device, the brackets 8 are clamped to the sides of the carriage by the bolts and wing nuts 10

35 so that the sections of the bar 12 and 14 extend transversely of the carriage in a position above the infant. The rack bar 22 is then placed between the disks 17 after the nursing bottle has been clamped to the lower end of the rack bar, the upper end of the rack bar resting on the bar 12 and the rack bar is then adjusted into a desired position by sliding the rack bar vertically or by swinging the rack bar about the axis of the bar 12 and securing the rack bar in its adjusted position by inserting one or more pins 20 through the openings 19 of the disks so as to engage the teeth of the rack bar.

35 The entire holder may be easily and quickly removed from the carriage by loosening the bolts and wing nuts 10—10 and sliding the brackets upwardly out of engagement therewith.

Eyes 28 on one of the bars 11 serve to hold the pins 20 and 21 when not in use.

It is believed that the details of construction and manner of use of the device will be read-

ily understood from the foregoing without further detailed explanation.

Having described the invention, what is claimed as new is:

1. A nursing bottle holder for baby carriages comprising a bar disposed transversely of the top of the carriage, means for removably securing the ends of the bar to the carriage, an arm having a nursing bottle secured to one end thereof and provided with a toothed edge, a disk carried by the bar, said arm resting on the bar at one side of the disk, and means carried by the disk and with which the teeth of the arm is selectively engageable for securing the arm in a swingably adjusted position about the axis of the disk.

2. A nursing bottle holder for baby carriages comprising a bar disposed transversely of the top of the carriage, means for removably securing the ends of the bar to the carriage, an arm having a nursing bottle secured to one end thereof and resting on the bar, a disk carried by the bar, and means for securing the arm to the disk for swingable adjustment of the arm about the axis of the disk.

3. A nursing bottle holder for baby carriages comprising a bar composed of telescoping sections, means for securing the outer ends of the bar to the sides of a carriage, a pair of disks mounted in spaced relation on the bar, an arm resting on the bar and having a nursing bottle secured to one end thereof and means carried by the disks and engageable with the arm for securing the latter in swingably adjusted position about the axis of the disks.

4. A nursing bottle holder for baby carriages comprising a bar composed of telescoping sections, means for securing the outer ends of the bar to the sides of a carriage, a pair of disks mounted in spaced relation on the bar, an arm having a nursing bottle secured at one end thereof, said arm being positioned between said disks and having teeth on one edge thereof, said disks having circumferentially arranged openings, and pins selectively inserted in said openings and engaged with the teeth of the arm to secure the arm in a desired position of adjustment on said disks.

JOHN JACOB LAWRENCE.
